UNITED STATES PATENT OFFICE.

HAROLD W. FLETCHER, OF HOUSTON, TEXAS, ASSIGNOR TO HUGHES TOOL COMPANY,
OF HOUSTON, TEXAS, A CORPORATION OF TEXAS.

WELL PACKER.

Application filed October 22, 1921. Serial No. 509,645.

To all whom it may concern:

Be it known that I, HAROLD W. FLETCHER, a citizen of the United States, residing at Houston, Harris County, Texas, have ⁵ invented a certain new and useful Improvement in Well Packers, of which the following is a full, clear, and exact description, such as will enable others skilled in the art to which it appertains to make and ¹⁰ use the same.

My invention relates to an improvement in well packers for special application to closing the space between the ends of casing in well drilling. When a smaller size of ¹⁵ casing is set inside a larger outside casing in the well it is necessary to close the space between the upper end of the small casing and the lower end of the larger casing, outside thereof by means of a packer. It is ²⁰ for this purpose that my present invention is especially adapted. It constitutes an improvement upon the packer set forth in my Patent No. 1,336,738, granted April 13, 1920.

²⁵ The object of my invention is to provide a means for lowering the casing and packer into the well, and for expanding the packer before the inserting means is withdrawn from the well.

³⁰ The principal improvement covered by my invention involves the using of a setting mandrel on the lower end of the pipe by means of which the casing is lowered into the well, this mandrel having a lower threaded surface thereon for attachment to the packer and an enlarged tapered surface ³⁵ above the packer by means of which the said packer may be expanded.

Referring to the drawing herewith in ⁴⁰ which like parts are designated by like numerals of reference as far as possible in the several views, Fig. 1 is a central longitudinal section through a casing and packer showing my improved mandrel attached thereto, said mandrel being shown in elevation. Fig. 2 is a similar view showing the parts in different positions and Fig. 3 is a similar view showing a slightly different embodiment of my invention.

⁴⁵ In the embodiment shown in Figs. 1 and 2 I have shown an inner casing 4 lowered downwardly into an outer casing 5. The inner casing 4 has a packer thereon by means of which it is intended that the space between the inner casing 4 and the casing 5

may be sealed so that it will be fluid tight. For this purpose there is an outwardly flaring sleeve 6 connected by means of a coupling 7 to the upper end of the inner casing. The sleeve 6 is cylindrical at the lower end ⁶⁰ thereof but is flared outwardly at 8 toward the upper end. Outside of said flaring sleeve 6 is a compressible sleeve 9 of soft metal, such as lead or babbitt, or some similar composition. The sleeve 9 rests at its ⁶⁵ lower end on a ring or washer 10 which in turn is supported upon the upper end of the coupling 7. The sleeve 9 is beveled inwardly at its upper end to receive the flaring portion of the sleeve 6. The outer surface ⁷⁰ of the sleeve 9 is therefore cylindrical.

The inner surface of the sleeve 6 is of the smallest diameter at the lower end of the tapered portion and is there threaded at ⁷⁵ 20 for attachment to the lower threaded end 21 of a setting mandrel 11, by means of which the packer is lowered into the well. The said mandrel has a cylindrical body threaded at its lower end and at the upper end is flared outwardly to provide a tapered head ⁸⁰ 12. Above the tapered portion the head is cylindrical and is provided with an internal recess for attachment to a pipe or drill stem 13. The central portion of the mandrel is formed with an interior channel ⁸⁵ 14 therethrough to allow the passage of fluid.

In the operation of this embodiment of my invention the packer is secured in the upper end of the casing 4 and the mandrel screwed into the throat 20 of the sleeve of ⁹⁰ the packer and the said mandrel is then attached to the pipe or drill stem 13. The casing, and packer thereon, is then lowered into the well until the inner casing is seated upon the bottom thereof. The threaded ⁹⁵ connection between the mandrel and the packer is the usual right hand thread and it is then possible, by turning the mandrel in the right hand direction, to force the same downwardly into the packer and casing 4. When the threaded connection is thus released the dropping of the pipe 13 and mandrel thereon into the upper throat of the packer will force the sleeves 8 and ¹⁰⁰ 9 outwardly against the casing 5 so as to seal the space between the same and the casing 4. A continued reciprocation of the mandrel will drive the packer outwardly with sufficient force to compress the sleeve ¹⁰⁵ 9 between the inner sleeve 8 and the casing ¹¹⁰ 5

5 so that no fluid can escape between the walls of the two casings. When this has been done the upper end of the ductile sleeve 6 will be expanded sufficiently, as shown in
5 Fig. 2, to force the threaded portions outwardly and to thus allow the upward passage of the lower end of the mandrel in an obvious manner. It will then be possible to withdraw the pipe 13 and mandrel
10 11 from the well, leaving the packer in adjusted position.

In Fig. 3 I have shown a second embodiment of my invention. The coupling 7', which connects the sleeve 6' with the inner
15 casing 4, is somewhat elongated and has, at its lower end, at the point where it is connected to the casing 4, a shoulder 15. The compressible sleeve 9 and the mandrel 11' are identical with the construction
20 shown in Figs. 1 and 2, except that the lower end of the mandrel is somewhat elongated and is threaded at 16 by a left hand thread and to this threaded end is secured a short collar 17. The upper end of this
25 collar is toothed, as shown at 18, the said teeth being vertical on one side and inclined on the other, as shown. The lower end of the sleeve 6' is also toothed at 19 to interfit with the teeth 18 of the collar 17.

30 In this embodiment the mandrel 11' is inserted downwardly through the sleeve 6' to the position shown in Fig. 3. The coupling 7' is secured to the upper end of the casing 4, and before the sleeve 6' is attached thereto, the collar 17 is secured to the lower end of the mandrel. The sleeve 6' is then secured in position by being screwed into the upper end of the coupling 7' with the compressible sleeve 9 and washer 10 outside
35 thereof. The casing 4 is then lowered downwardly into the well, the collar 17 serving to support the same on the mandrel while it is being introduced into the casing 5. When the casing 4 has been properly seated the reciprocation of the mandrel will bring the tapered surface 12 thereon into forcible contact with the flared upper end of the packer and expand it, as previously described. When the packer has been properly sealed the mandrel may be drawn upwardly until the toothed upper end 18 of the collar 17 meshes with the toothed lower end 19 of the packer sleeve. The rotation of the pipe 13 and the mandrel thereon in
40 a right hand direction will then serve to unscrew the collar 17 from the mandrel and allow the mandrel to be withdrawn. The collar 17 will then remain seated on the shoulder 15, but will not interfere with the
45 further work of the well.

It will be noted that the shoulder 15 will also serve as a stop for the mandrel during the expansion of the packer to indicate when the packer has been sufficiently expanded. When the mandrel has worked its

way downwardly into the packer for a distance sufficient to bring the lower end of the collar 17 into contact with the shoulder 15, the setting of the packer will be complete. This will prevent undue expansion of the packer and will indicate to the driller when the mandrel is to be withdrawn.
70

The advantages of this type of packer and the means by which it is set in position, as described, will be obvious to one skilled in
75 the art. It is commonly necessary to place a packer in position and then withdraw the pipe by means of which the packer was properly placed and insert an expanding
80 spear to properly seal the packer between the casings. In my construction these two operations may be combined so that it will not be necessary to go down again into the hole to expand the packer after it has been seated. This will result in a large saving of
85 time and expense and will secure a more positive and accurate setting of the packer so as to seal the space between the casings.

Having thus described my invention, the further objects and advantages of which
90 will be apparent to one skilled in the art, what I claim as new and desire to protect by Letters Patent, is:

1. In combination with a well packer comprising a coupling, a sleeve of ductile metal
95 thereon, the upper end of which is flared outwardly, a packing sleeve of compressible material outside said metal sleeve; a mandrel for setting and expanding said packer comprising a lower tubular cylindrical end, 100 a frusto-conical expanding head at the upper end and means on the said lower end to engage said packer and releasable therefrom by the rotation of said mandrel.

2. The combination with a well packer
105 having a coupling, a flaring sleeve of ductile metal thereon, and a sleeve of compressible metal outside said flaring sleeve, of a mandrel having means thereon to secure
110 said mandrel to said packer, a downwardly tapering surface on said mandrel above said sleeve whereby said sleeve may be expanded, said mandrel being adapted to be withdrawn from said packer after the expansion of said
115 packer by said mandrel.

3. A packer for sealing the connection between the end of a casing with a larger casing outside thereof, comprising a coupling, an upwardly flaring sleeve thereon, a sleeve of compressible metal outside said flaring sleeve, and a combined mandrel and setting tool comprising a tapered expanding member and a lower attaching member adapted to detachably support said packer on said
120 mandrel and to be released for withdrawal when said packer is set, by the rotation of said mandrel.

4. The combination with a well packer having an elongated coupling thereon, a flaring ductile metal sleeve on the upper end
125

- thereof, and a compressible sleeve outside said flaring sleeve, of a setting mandrel adapted to fit slidably in said flaring sleeve, releasable means on said mandrel to prevent removal of said mandrel from said packer while the same are being introduced into the well, means on said mandrel to expand said packer, said mandrel being adapted, when released, to be withdrawn from the well.
5. In a well packer, the combination of an interior casing and a flaring ductile sleeve at the upper end thereof, with a setting mandrel slidable in said sleeve, a collar on the lower end of said mandrel, the upper end of which is toothed, a tapered head on said mandrel above said sleeve to expand said sleeve, and teeth on the lower end of said sleeve adapted to interfit with said toothed collar, to hold said collar so that it may be released and said mandrel withdrawn.
6. In a well packer, the combination of a coupling having an interior shoulder at the lower end thereof, an expanding sleeve at the upper end of said coupling, and a mandrel slidable in said sleeve and having a collar on its lower end reciprocable between said sleeve and said shoulder, means on said mandrel to expand said packer sleeve and means on said sleeve and collar whereby said collar may be removed and said mandrel released.
7. In a well packer, the combination of an interior casing, an elongated coupling thereon, an expanding packer sleeve at the upper end thereof, with a mandrel slidable through said sleeve, releasable means on said mandrel to prevent withdrawal of said mandrel from said sleeve, means on said mandrel to expand said packer sleeve, and means to limit the downward movement of said mandrel.

In testimony whereof, I hereunto affix my signature, this the 18th day of October, A. D. 1921.

HAROLD W. FLETCHER.
